UNITED STATES PATENT OFFICE.

JOHN HENRY MILTON BROWN, OF VICKSBURG, MISSISSIPPI.

LEVELING DEVICE.

1,125,807.

Specification of Letters Patent.

Patented Jan. 19, 1915.

Application filed November 9, 1912. Serial No. 730,441.

To all whom it may concern:

Be it known that I, JOHN H. M. BROWN, a citizen of the United States, residing at Vicksburg, in the county of Warren and State of Mississippi, have invented new and useful Improvements in Leveling Devices, of which the following is a specification.

An object of the invention is to provide a leveling device, particularly adaptable for 10 use on pool and billiard tables for leveling the playing surfaces thereof.

The invention embodies, among other features, a structure preferably arranged within the legs or supporting members of a table 15 or other article of furniture and whereby the height of the article of furniture from the floor can be varied in order to level the plane surface thereof.

In the further disclosure of the invention 20 reference is to be had to the accompanying drawings, constituting a part of this specification, in which similar characters of reference denote corresponding parts in all the views, and in which:

25 Figure 1 is a fragmentary vertical sectional view of a billiard table, showing my device used in connection therewith; Fig. 2 is a horizontal sectional view taken on the line 2—2 in Fig. 1; and Fig. 3 is a perspective view of the traveler.

Referring more particularly to the views, I disclose a portion of a table 10 and a leg or supporting member 11 thereof, the said leg being preferably hollow and having 35 arranged therein a casing 12, with a block 13 arranged to slide in a hollow portion of the leg 11, beneath the casing 12, and normally reposing on the floor which also supports the leg of the table, a plate 14 being 40 secured to the upper end of the block 13 and having projecting upwardly therefrom a bolt 15, the free end of which is threaded into a wedge member 16, to support the same within the casing 12, suitable cushion

45 springs 17 being placed within the casing, with the upper ends thereof abutting against the under face of the wedge member 16 to aid in supporting the wedge member within the casing and also cushion the same, thus 50 taking up the slight play which might occur between the threaded portion of the bolt 15 and the wedge member. A second wedge member 18 is secured to the under side of the top of the casing 12, in an inverted position so that the inclined faces 19 and 20 of 55 the wedge members 16 and 18 respectively

will be arranged in opposite relation to form a chamber 21, the upper and lower walls of which are inclined as shown. A screw rod 22 extends within the casing 12 and threaded on the screw rod is a traveler 24, the said traveler being operable in the chamber 21 and interposed between the wedge members 16 and 18, the other end of the screw rod being adapted to extend exteriorly 60 of the casing and project into an elongated opening 22^a formed in the supporting member 11. Now it will be apparent that when the screw rod is actuated by means of a suitable wrench or the like, the opposed faces 65 of the traveler will operate over the inclined faces 19 and 20 of the respective wedge members 16 and 18, suitable bearings 25 being preferably arranged upon the traveler 70 in order to reduce the friction between the inclined faces of the traveler and the inclined faces of the wedge members 16 and 18.

Now referring to the views, it will be seen that when a wrench or other instrument is placed in the recess 23 to grip the screw rod 80 22 and rotation is imparted to the screw rod, the traveler 24 will be advanced or retreated in the chamber 21 to raise or lower the table 10 and likewise the leg 11 thereof, it being readily understood that when the 85 traveler is moved toward the wrench-applying end of the screw rod, the traveler bearing against the inclined face of the wedge member 16 will exert an upward movement on the inclined face of the wedge member 18, 90 whereas when the traveler is retreated in the chamber 21, the weight of the table 10 bearing down upon the wedge member 18 will cause the leg 11 and table 10 to sink or lower, as the traveler is retreated in the 95 chamber. As mentioned heretofore, the springs 17 are provided to aid in properly seating the wedge member 16 and cushioning the same so that a fine adjustment of the table can be obtained, it being understood 100 that each leg of the table is provided with an independent leveling device such as described, in order that the plane surface of the table can be properly leveled. When the table has been leveled, a disk 26 of an ornamental design is preferably mounted upon the leg of the table by means of glue or in any other convenient manner to cover the recess 23, thus preventing dust and dirt from entering the casing 12 and also resulting in the neat appearance of the table and 105 the supporting members thereof.

Although I have described my device as used in connection with a billiard table, it will be understood that the same can be conveniently employed in leveling various structures and articles of furniture.

Having thus described my invention, I claim:

In combination with a hollow supporting leg, a casing in the upper part of the hollow portion of the leg, said casing being provided with a slot in register with a slot in the leg, and an opening communicating with the slot in the leg, a central leg member 10 slideable in the hollow portion of the leg, a bolt projecting upwardly from the central leg member and into the casing, a horizontal wedge member supported on the bolt and lying wholly within the casing, a second wedge member in opposed relation to the 15 first wedge member and lying wholly within 20

the casing so that the inclined faces of the wedge members will be opposed to form a tapering chamber, a screw rod in the casing and projecting through the slot in the casing and the slot in the leg, with the free end 25 of the screw rod providing a handle portion and lying wholly within the opening and communicating with the slot in the leg, a traveler threaded on the screw rod and operable in the chamber over the inclined faces 30 of the wedge members, and ball bearings on the traveler and supported on the opposed surfaces thereof to contact with the inclined faces of the wedge members.

In testimony whereof I affix my signature 35 in presence of two witnesses.

JOHN HENRY MILTON BROWN.
